UNITED STATES PATENT OFFICE.

AXEL J. ROSELL, OF NEW YORK, N. Y.

SAFETY DEVICE FOR ELEVATORS.

1,171,253.

Specification of Letters Patent. Patented Feb. 8, 1916.

Application filed February 4, 1915. Serial No. 6,044.

To all whom it may concern:

Be it known that I, AXEL J. ROSELL, a citizen of the United States, and a resident of the city of New York, borough of Brooklyn, 5 in the county of Kings and State of New York, have invented a new and Improved Safety Device for Elevators, of which the following is a full, clear, and exact description.

10 The object of the invention is to provide a new and improved safety device for elevators arranged to prevent accidental opening of a shaft door unless the cage has reached and stopped at a landing, and to 15 lock the controller in the cage against being actuated while the cage is at a landing unless the door for this landing is first in closed position.

In order to produce the desired result use 20 is made of a lock for normally holding the door against opening, and an actuating mechanism mounted in the cage and having an operating member connected with the controller in the cage, the said operating 25 member being adapted to engage the said lock on the cage reaching a landing with a view to unlocking the door to allow the operator to move the door into open or closed position, the said actuating mechanism also having 30 a locking member controlled by the door on opening and closing the same and adapted to lock the said controller against movement as long as the door is open and to unlock the controller as soon as the door is 35 closed.

A practical embodiment of the invention is represented in the accompanying drawings forming a part of this specification, in which similar characters of reference indicate 40 corresponding parts in all the views.

Figure 1 is a sectional side elevation of the safety device as applied and showing the cage in position at a landing, the door of which is shown in closed position; Fig. 2 is 45 an inverted sectional plan view of the same on the line 2—2 of Fig. 1; Fig. 3 is a cross section of the same on the line 3—3 of Fig. 2; Fig. 4 is an inverted plan view of the safety device, similar to Fig. 2, and showing 50 the parts in a different position; Fig. 5 is a sectional side elevation of the safety device as applied and showing the parts in position after the cage has left the landing; Fig. 55 6 is an inverted sectional plan view of the same on the line 6—6 of Fig. 5; and Fig. 7 is a perspective view of the spring catch.

In the elevator shaft A is mounted to ascend and descend in the usual manner a cage B provided with a suitable controller C for controlling the up and down movement of the cage. A door D leads to the shaft A at each landing E, and this door is provided at its lower end with a vertically disposed locking arm F, normally abutting against a lug G' of a spring catch G extending horizontally and secured to the inside of the shaft A at the landing E. Normally the door D is locked against opening by a locking bar F abutting against the lug G' of the spring catch G.

On the under side of the cage B is arranged a slide H provided with elongated slots H' through which extend bolts H² attached to the under side of the cage B so as to allow sliding of the slide H toward and from the side of the shaft A having the doors D. The slide H is pivotally connected with one end of a link I connected by a pivot I' with another link I² fulcrumed on a bracket I³ attached to the under side of the cage B. The pivot I' is pivotally connected by a connecting link J with an arm C' on the lever C² of the controller C so that when the said lever C² is actuated by the attendant in charge of the cage B then a movement is given to the slide H to move the same toward or from the side of the shaft H containing the door D.

The slide H is provided with a sliding arm K pressed on by a spring K' and carrying a friction roller K² adapted to engage the free end of the spring catch G to move the latter into unlocking position, that is, to move the lug G' out of the path of the locking bar F to permit opening of the door.

D. On the slide H is fulcrumed at L' a lever L terminating in a fork L² adapted to engage the locking bar F at the time the cage B reaches a landing E and the slide H is moved outward so that the door on being opened imparts a swinging motion to the lever L to swing the same from its normal position shown in Fig. 2 into the locking position illustrated in Fig. 4. The rear end of the lever L is provided with a lug L³ adapted to engage a notch J' formed in the connecting link J to lock the controller lever C² against movement, that is, at the time when the lever C² is in vertical position and the cage B is at a standstill (see Fig. 1).

The operation is as follows: When the

cage B is ascending or descending then the controller lever C² is either in the position shown in full lines in Fig. 5 or in dotted lines as indicated in said figure. When the controller lever C² is in this position then the slide H is in withdrawn position so that the fork L² of the lever L and the friction roller K² extend within the area of the bottom of the cage B and consequently do not interfere with the ascending and descending of the cage B. When the cage B reaches a landing and the attendant moves the lever C² into vertical stopping position then the connecting link J straightens out the links I, I² so that an outwardly sliding movement is given to the slide H whereby the fork L² is engaged with the locking bar F and the friction roller K² is engaged with the free end of the spring catch G to move the lug G' out of the path of the locking bar F. When the elevator comes to a stop the door D can be opened by the attendant in the cage and the door in its opening movement causes the locking bar F to impart a swinging motion to the lever L by the locking bar F engaging one of the prongs of the fork L². The swinging motion given to the lever L causes its lug L³ to enter the notch J' so that the controller C is locked against movement during the time the door D is in an open position. When the door D is closed the locking bar F reengages the fork L² and imparts a return swinging motion to the lever L so that the lug L³ thereof moves out of the notch J' at the time the door D is in closed position. When this takes place the controller C can be manipulated by the attendant for starting the car and in doing so the slide H is withdrawn to move the friction roller K² out of engagement with the spring catch G whereby the latter returns to normal locking position thus preventing the door D from being opened on account of the lug G' projecting into the path of the locking bar F.

From the foregoing it will be seen that the locking bar F and the spring catch G are on the door and elevator shaft respectively, while the remaining member of the safety device are located on the cage.

In case the operator stops the cage intermediate of two landings the projected roller K² and the fork L are not liable to interfere with any projection in the shaft, as the spring K' allows the arm K carrying the roller K² to yield.

Having thus described my invention, I claim as new and desire to secure by Letters Patent:

1. An elevator shaft having a door provided with a lock to normally hold the door against opening in combination with a cage adapted to ascend and descend in the said shaft, a controller in the said cage and an actuating mechanism mounted on the said

cage and having a notched member connected with the controller, and an operating member connected with the notched member and adapted to engage the said lock on the cage reaching a landing, to unlock the door to allow of moving the door into open or closed position, the said actuating mechanism having a locking member controlled by the door on opening and closing the same and adapted to engage the said notched member to lock the said controller as long as the door is open and to disengage the notched member to unlock the controller as soon as the door is closed.

2. An elevator shaft having a sliding door provided with a locking bar, and a spring catch held on the shaft and adapted to normally engage the said locking bar to hold the door against opening in combination with a cage adapted to ascend and descend in the said elevator shaft, a controller in the cage and actuating mechanism mounted on the cage and connected with the said controller to unlock the door and to lock the controller, the said actuating mechanism having a link connected with the controller, an operating member connected with the said link and adapted to engage the said catch to move the latter into unlocking position relative to the locking bar to allow of opening or closing the door at the time the cage reaches a landing and the said actuating mechanism having a fulcrumed locking member controlled by the said locking bar and adapted to engage and disengage the said link, lock the controller against movement as long as the door is opened and to unlock the controller as soon as the door is closed.

3. An elevator shaft having a sliding door provided with a centrally disposed locking bar and a spring catch held on the shaft and normally engaging the said locking bar to hold the door against opening, combined with a cage adapted to ascend and descend in the said shaft, a controller in the said cage, a slide mounted on the cage and connected with the said controller, the said slide having a spring pressed sliding member adapted to engage the said spring catch and move the same into unlocking position relative to the locking bar, and a locking lever fulcrumed on the said slide and having at one end a fork adapted to engage the said locking bar and to receive a swinging motion on moving the door into open or closed position, the said locking lever having a member at the other end adapted to engage the said controller and lock the same against movement during the time the door is open.

4. An elevator shaft having a sliding door provided with a vertically disposed locking bar, and a spring catch held on the shaft and normally engaging the said locking bar

said locking bar and
otion on opening and

to hold the door against opening, combined
with a cage adapted to ascend and descend
in the said shaft, a controller in the said
cage, a slide mounted on the cage and con
nected with the said controller, the said
slide being provided with a spring-operated
friction roller adapted to engage the said
spring catch and move the same into unlock
ing position relative to the locking bar, and
10 a locking lever fulcrumed on the said slide
and having at one end a fork adapted to
engage the said locking bar and to receive a
swinging motion on moving the door into
open or closed position, the said locking
15 lever being adapted to engage the said controller
and lock the same against movement
during the time the door is open.
5. An elevator shaft having a sliding door
provided with a vertically disposed locking
bar and a spring catch held on the shaft and
normally engaging the said locking bar to
hold the door against opening, combined
20 with a cage adapted to ascend and descend
in the said shaft, a controller in the said
cage, a slide mounted on the cage and adapt
ed to engage the said spring catch, a pair of
connected links of which one is fulcrumed
25 on the cage and the other is connected with
the said slide, a connecting link connecting
the said pair of connected links with the
controller, the said connecting link having
a notch, and a locking lever fulcrumed on
30 the said slide and having at one end a fork

adapted to engage the
to receive a swinging m
closing the door, the o
locking lever being ad
